DRINKING MUG OR SIMILAR ARTICLE

William C. Klenk III, Philadelphia, Pa.

Application July 30, 1956, Serial No. 42,460

Term of patent 3½ years

(Cl. D44—9)

Fig. 1 is a front elevational view of a drinking mug or similar article showing my new design.

Fig. 2 is a side elevational view thereof.

Fig. 3 is a sectional view taken along the lines 3—3 in Fig. 1.

Fig. 4 is a sectional view taken along the lines 4—4 in Fig. 1.

I claim:

The ornamental design for a drinking mug or similar article, substantially as shown.
